ROUND CORNER

Richard H. Crouch, Pulaski, Va., assignor to
Automatic Machinery Corporation, Pulaski,
Va., a corporation of Virginia

Application April 13, 1936, Serial No. 74,200

3 Claims. (Cl. 20—92)

My invention relates to an improvement in round corners.

Round corners for cabinet work have been a subject of steady and slow development, and 5 various attempts have been made to provide a corner in which the outer surface is made of veneer or plywood, which will be rigid, smooth, solid, durable and uniform throughout its outer and rounded surface without bulging at the ends 10 of the corner post or core.

The patent to Berg, No. 1,981,494, dated November 20, 1934, discloses different forms for accomplishing this end, and in a modification of the preferred form he shows the corner post, 15 with a specially formed groove at each edge adapted to interlock and interfit with counterpart grooves in the inner edges of the side members which go to form the corner construction, but in this type of structure there are two objections which are overcome by my present invention:—

(1) One objection is that it presents a weakness at the outer edges of the corner post, which sooner or later results in bulging at those two 25 points due to the pressure applied in forming the corner structure; and

(2) The second defect is that it is impossible in this form of structure to pull or bend the relatively thin veneer or plywood section around the 30 outer curved surface of the corner post because it is in the nature of a lock joint.

In my corner the workman can lay the core or corner post in the cut and clamp all parts together in one operation. Thus in my invention 35 I have overcome both the foregoing objections by preventing bulging at the joints, and by my method of construction I can pull or bend the relatively thin section of veneer or plywood around the corner piece, or, if preferred, I can 40 slide the latter lengthwise into the space formed therefor as is necessary in the Berg construction.

One object of my invention is to provide a device of this type and a method whereby to produce a smooth, symmetrical, rounded surface at 45 the corner joint formation for use in the manufacture of different articles of furniture, wagon-boxes, and the like.

With the foregoing objects in view, this invention consists in a corner made by inserting a 50 filler core block having an outer surface shaped to the corner form desired, and the edges fashioned to fit corresponding edges of a recess extending transversely through a strip of the material of which the corner is formed, at the back 55 of which recess is left a thin, flexible portion

adapted to be drawn around the curved surface of the filler or block, whereby the counterpart edges of the latter and the recess are brought together and securely held to complete the curved corner structure.

In the accompanying drawing:

Fig. 1 is a view in perspective showing a transversely recessed strip with a thin portion left at the back and a filler core block in position to be inserted in the recess;

Fig. 2 is an illustration showing how the recesses of this type may be formed;

Fig. 3 is a view in perspective of the completed corner;

Fig. 4 is a plan view of the same; and

Fig. 5 is a view illustrating the preferred method of laying the core or corner-post in the cut and clamping all parts together in one operation.

The numeral 1 represents a core of material such as wood, preferably faced on both sides with 20 veneer or plywood 2 and 3, and 4 is a recess which might be variously formed, as for instance by a cutter-head 5. This recess 4 is of a depth to leave the plywood or veneer 3 intact, and the edges 7 of the recess are irregularly grooved as 25 illustrated. A filler core block 8 has an outer surface 9 shaped to the form of corner desired, preferably in the arc of a circle as illustrated, and this block 8 is provided with irregular shaped edges 10, which conform to and are a counter- 30 part of the edges 7 of the recess 4.

The recess 4 is initially of greater width than the block 8 as illustrated in Fig. 1, but when the ends of the strip 2 are brought around to the positions shown in Figs. 3 and 4, the part 6 is 35 drawn tightly around the curved surface 9 of the block 8, and the edges 10 of the straight and inner surface 11 of the block 8 are snugly and securely embraced and held in the position shown in Figs. 3 and 4. The foregoing is made 40 possible by reason of the specially planned edge groove formation of the filler core block 8, which will permit of the ends 1 being swung around in arcs of circles sprung from a point at or near the center of the block 8, and from an initial 45 position such as illustrated in Fig. 1 to that shown in Figs. 3 and 4. This is made possible by reason of the precise transverse shape or contour of the filler core block from the ends of curved surface 9 transversely all the way round the grooved 50 edges and the flat or straight inner surface 11.

One of the desirable features of my present invention is to create a substantially uniform pressure between the points marked *a* and *b* and *c*, and this is accomplished by pulling the flex- 55

ible part 6 around the curved surface 9 of the 5
filler core block 8 with the result that it allows the
quarter circle at the corner to assume a smooth
and regular form without causing a bulge at the
points marked *d*, which has been the difficulty
and a real problem in previous types of corner
joints.

While I have described and illustrated a plan
of cutting the recess 4 transversely through a
10 strip as illustrated in Fig. 2, it is perfectly ob-
vious that the ends 1 might be made separately
with the edge grooves 7 and glued to the plyn-
wood or veneer 3 at the proper distance apart,
thereby making provision for the recess 4.
15 Either plan would come within the scope of my
invention.

It is obvious that glue may be applied to all
of the contacting surfaces of the joint before
the parts are pulled around the filler core block.

20 In Fig. 5, I have attempted to illustrate my
preferred method of infolding and clamping the
core or corner post, and it consists in inserting a
block 8 in the recess in any convenient way either
25 endwise or edgewise, and then bringing the ends
1 around as illustrated in dotted lines, where-
upon the long beveled edge 15 of the ends 1 will
engage the beveled edges 16 of the filler core
block 8, the two surfaces 15 and 16 having a
30 sliding cam action upon each other, with the
result that the block 8 is centered and approxi-
mately uniform pressure is applied thereon at
every contacting point by the time the ends 1
are brought into place as illustrated in Fig. 4,
35 thus giving a continuous and uniform curvature
to the corner, and maintaining the shape thus
imparted by the formation as a result of the

complete interlock and uniform distribution of
pressure throughout.

I claim:

1. A construction of the class described comprising, two sides located adjacent a corner and 5
having undercut grooves near their adjacent edges, a corner post interposed between the adjacent edges of the sides and abutting thereagainst and having integral tongues extending into said undercut grooves and an outer lamination 10 attached to the outer surfaces of said sides and extending continuously around the outer surfaces of said corner post.

2. A construction of the class described comprising, two sides located adjacent a corner and 15
having undercut grooves in their inner surfaces, a corner post interposed between the adjacent edges of the sides and abutting thereagainst and having integral tongues extending into said undercut grooves and an outer lamination at 20 attached to the outer surfaces of said sides and extending continuously around the outer surfaces of said corner post.

3. In a construction of the character described comprising two sides connected by a relatively 25
thin flexible strip, the edges of the sides adjacent to the flexible strip undercut at approximately right-angles next to the flexible strip, then in the direction of the sides and approximately parallel therewith, then at approximately right- 30
angles to the flexible strip and finally toward each other at an obtuse angle in combination with a core having a rounded surface around which the flexible strip is bent and having its remaining portion cut to fit the under cut angles 35
of the sides.

RICHARD H. CROUCH.
